his Attorney.*

UNITED STATES PATENT OFFICE.

CAMILLO MACCHIA, OF ARDMORE, PENNSYLVANIA, ASSIGNOR TO THE UNITED STATES FIRE WORKS MANUFACTURING COMPANY, OF CARDINGTON, PENNSYLVANIA, A CORPORATION OF PENNSYLVANIA.

TOY TORPEDO.

Application filed March 15, 1921. Serial No. 452,466.

To all whom it may concern:

Be it known that I, CAMILLO MACCHIA, a citizen of the United States of America, and resident of Ardmore, in the county of Montgomery, State of Pennsylvania, have invented a certain new and useful Improvement in Toy Torpedoes, of which the following is a true and exact description, reference being had to the accompanying drawing, which forms a part thereof.

My invention relates to torpedoes of the kind intended to be exploded on being thrown against the ground or a wall and the object of my invention is to provide such a torpedo with a definite holding capacity for the explosion and gravel forming its charge and a wall strength which can be accurately determined and which will insure sufficient resistance to the expansive power of the gases generated when the explosive is ignited to insure that when the container bursts a loud explosive noise will occur.

The nature of my improvement will be best understood as described in connection with the drawing in which

Figure 1 is a vertical central sectional elevation of my torpedo, and

Figure 2 a section on line 2—2 of Fig. 1.

A is a cylindrical container formed of multiple windings of paper indicated at a, a. B and B' are cup like closures of a strong tough material formed with peripheral flanges b, b' which fit over the ends of the container A. The closures B, B', must be strong enough to offer a resistance to a bursting strain equal to that necessary to insure the volume of sound desired on the explosion of the torpedo. C, indicates the charge of explosive in the torpedo and D the charge of gravel with which the explosive container is loosely filled. E is the outer wrapping of the torpedo made up of multiple windings e, e, of paper glued together and glued to the container A and the flanges b and b' of the closures B, B'. The tubular wrapper E being made sufficiently strong and sufficiently firmly attached to the closures to insure that the closures will not be blown off of the ends

of the container when the explosive is ignited and therefore to insure that the expanding gases will burst through the wall of the container or through the heads of the closures or both.

In constructing my torpedo the container A is formed by winding a strip of paper on a mandrel the windings e being at least partly secured together by glue, a closure B is slipped over the lower end of the container and a measured charge C of explosive inserted, after which the container is filled up with gravel and a closure B' slipped over its top. Finally, a strip of paper glued on its inside is wound around the container and the flanges b and b' of the closures forming an outer tubular wrapper E made up of multiple windings e of paper strong enough and strongly enough attached to the closure flanges to prevent their being blown off when the explosive ignites.

By preference the strength of the wall of the container A together with the strength of the wrapper E should be about equal to that of the closures so that the heads and walls of the container will burst as nearly as possible at the same time.

It will be obvious that my torpedoes are of equal capacity, symmetrical shape, easily and safety transportable and so designed as to insure uniform explosive qualities and a maximum noise on explosion.

Having now described my invention, what I claim as new and desire to secure by Letters Patent, is:

1. A torpedo consisting of a cylindrical container formed of multiple windings of paper, cup like closures for the ends of said container formed of strong, tough material flanged to fit over the ends of the container, a wrapper formed of multiple windings of paper glued to the outer wall of the container and to the flanges of the closures, the windings of said wrapper being glued together and a charge consisting of an explosive powder and gravel filling the container.

2. A toy torpedo comprising a paper shell consisting of a short length of tube, snugly

fitting flanged cap members secured to the ends of the tube and forming closures at each end thereof, and a mixture contained therein adapted to be exploded when the torpedo is subjected to shock.

3. A toy torpedo comprising a paper shell consisting of a short length of tube, snugly

fitting cap members having flanges glued to the outer surfaces at the ends of the tube and forming closures at each end thereof, and a mixture contained therein adapted to be exploded when the torpedo is subjected to shock.

CAMILLO MACCHIA.
